(57) **CLAIM**

The ornamental design for suction strainer, as shown and described.

DESCRIPTION

FIG. 1 is a perspective view of a suction strainer;

FIG. 2 is a front view thereof;

FIG. 3 is a rear view thereof; and,

FIG. 4 is a plan view thereof.

The dash-dot broken line shown in FIG. 3 depict boundaries of the claim and form no part thereof. The suction strainer is shown with a symbolic break in its length. The appearance of any portion of the article between the break lines forms no part of the claimed design.
